UNITED STATES PATENT OFFICE.

AUGUSTUS WILLIAM LOUIS SCHERMULY, OF SUTTON, ENGLAND.

MEANS FOR ATTACHING SHIPS' BOATS TO AND DETACHING THEM FROM TACKLE SUSPENDED FROM DAVITS OR THE LIKE.

1,319,492.

Specification of Letters Patent.

Patented Oct. 21, 1919.

Application filed September 12, 1919. Serial No. 323,422.

To all whom it may concern:

Be it known that I, AUGUSTUS WILLIAM LOUIS SCHERMULY, a subject of the King of Great Britain, residing at Stonecroft, Stone 5 Cot Hill, Sutton, in the county of Surrey, England, have invented new and useful Improved Means for Attaching Ships' Boats to and Detaching Them from Tackle Suspended from Davits or the like, of which the 10 following is a specification.

My invention relates to means for suspending and releasing ships' boats from falls, the said means being of the kind in which the falls and tackle blocks suspended 15 from the davits, are connected, by links, or the equivalent, to inclined hooks (one usually being a lever hook manipulated for release) secured to the boat, toward its ends, and a "fore-and-after" connected to the 20 lower ends of the said tackle, acts to prevent outward movement of the said ends of the tackle relatively to each other and thereby, until the boat is released, maintains the links, or the equivalent, in engagement with 25 their respective hooks, the release being effected by slackening a rope connection extending between the devices which connect the boat with the falls from the davits.

The object of my invention is to provide 30 simple and efficient means which will insure the boat taking the water on an even keel whatever may be the position the boat is in when released from the falls, and will also insure secure suspension of the boat, non-liability to accidental detachment, and rapid 35 release when required, while, obviating, or lessening, liability to the occupants of the boat being injured by the tackle when released.

According to my invention the falls and 40 lower blocks of the tackle by which the boat is suspended from the ships' davits are connected with the boat by links, or loops, engaging upwardly inclined hooks secured 45 to the boat, the said blocks being connected by a tie-rope, or "fore-and-after" made, or arranged, so that it can be, in effect, lengthened and shortened; it, when shortened, holding the said links, or loops, in engagement 50 with the said hooks and when lengthened allowing the links, or loops, under the weight of the boat, to slip from the said hooks, and release the boat. The tie-rope, or "fore-and-after," is provided with a very 55 simple device, as hereinafter described, by

means of which, by the removal of one simple securing device which holds two hinged parts parallel with each other, the tie-rope, or "fore-and-after" becomes lengthened and thus the release of the boat can be instantaneously effected by one person using one hand. 60

I will describe with reference to the accompanying drawing an arrangement in accordance with my invention. 65

Figure 1 is a longitudinal section of a boat with an arrangement according to my invention applied thereto. Figs. 2 and 3 show, in the shorter and longer positions respectively, the device by means of which the 70 effective length of the tie-rope, or "fore-and-after" is altered.

The said device consists of, or comprises, two members, one of which (that consisting of the two pieces marked A) is connected 75 (at B) by the pin a with the lower end of one of the tackle-blocks of the falls from the davits, the other member (that marked A^2) consisting of a slotted link, hinged to the inner end of the first mentioned member 80 A by the pin a^2 and engaged by a loop c or the like, connected with one end of the tie-rope, or "fore-and-after", C, the other end of which is connected (at B^2) to the tackle-block. The said members A and A^2 85 are foldable upon each other and capable of being secured in that position by a fastening such as the pin a^3 which, when removed from the holes at a^4 , will allow the members A and A^2 to open out from each other 90 upon the hinge pin a^2 which connects the said members. The pull on the tie-rope, or "fore-and-after" C tends to turn the link member A^2 , on the hinge pin a^2 to bring it into line with the other member A, but it is 95 normally held in its folded, and securing, position (Fig. 2) by the retaining pin a^5 (with which the projection a^6 in the member A^2 engages) but upon the release of the said pin a^5 , the said link member A^2 , under the 100 pull of the tie-rope, or "fore-and-after", C, turns upon the pin a^2 which connects it with the other member A (as in Fig. 3) and virtually lengthens the tie-rope, or "fore-and-after" C, so that the suspending tackle 105 is not then held in the securing position by the said tie-rope, or "fore-and-after" C, and the weight of the boat causes the hooks, E, or other securing means carried by the boat to slip off the links b or equivalents, of the 110

suspending tackle, and release the boat upon an even keel.

If desired, there may be a device, such as that described, at each end of the tie-rope, 5 or "fore-and-aft" C, but generally one only, as illustrated, will be preferable.

The aforesaid tie-rope, or "fore-and-aft" C can be arranged well above the position in which the occupants of the boat 10 would be, and the extensible device is so secured that its hinged member A² turns upward, or away, from the boat, so that liability to the occupants being injured by the tackle is obviated, while, as the tackle-blocks of the two falls remain connected, 15 they are easily laid hold of when the boat is to be attached to the falls.

What I claim is—

1. A boat supporting and releasing apparatus comprising a pair of inclined hooks secured at opposite ends of the boat and faced away from each other, a pair of davit falls, one for each hook, a slip member on each fall adapted to engage its hook, tie 20 means extending between the fall elements to hold said slip members in supporting engagement with the inclined hooks, and means for releasing said tie to permit the escape of the said slip members from the inclined 25 hooks under the weight of the boat.

2. A boat supporting and releasing apparatus comprising a pair of inclined hooks secured at opposite ends of the boat and faced away from each other, a pair of davit 30 falls, one for each hook, a slip member on each fall adapted to engage its hook, tie means extending between the falls, a take-up device arranged in said tie to draw said slip members into supporting engagement with 35 the inclined hooks, and means for releasing said take-up device to permit the tie to so

lengthen that the slip members escape the inclined hooks under the weight of the boat.

3. A boat supporting and releasing apparatus comprising a pair of inclined hooks 45 secured at opposite ends of the boat and faced away from each other, a pair of davit falls, one for each hook, a slip member on each fall adapted to engage its hook, tie 50 means extending between the falls, said tie means comprising a link adapted to be moved into overlapping position with relation to a coöperating member in the tie to draw said slip members into supporting engagement with the inclined hooks, and readily releasable means for engaging said link in said overlapping position but serving on release to free said link and permit the tie to 55 so lengthen that the slip members escape the inclined hooks under the weight of the boat. 60

4. A boat supporting and releasing apparatus comprising a pair of inclined hooks secured at opposite ends of the boat and faced away from each other, a pair of davit falls, one for each hook, a slip member on each fall adapted to engage its hook, tie 65 means permanently connected to and extending between said falls, a take-up device in the tie for drawing the slip members on the falls into supporting engagement with 70 the inclined hooks, and means for releasing said take-up to permit the tie to so lengthen that the slip members escape the hooks under the weight of the boat.

In testimony whereof I have signed my 75 name to this specification in the presence of two subscribing witnesses.

AUGUSTUS WILLIAM LOUIS SCHERMULY.
